GERARD A. DE VLEEG, OF ROCKFORD, ILLINOIS.

METHOD OF AND MACHINE FOR GRINDING ROTARY CUTTERS.

Application filed May 15, 1926. Serial No. 109,222.

The present invention relates to an improved method of and machine for grinding rotary cutters of the reamer type.

The present application is a continuation in 5 part of my application Serial No. 756,418 filed December 17, 1924.

The primary object of the invention is to provide a new and improved method of and machine for grinding and relieving reamers 10 having helical or inclined cutting edges lying in a cylindrical area.

A more specific object is to provide a novel method of and machine for grinding reamers having helical cutting edges by 15 means of which reamers may be provided that will not chatter when in use.

Heretofore reamers have first been ground cylindrically round, and have then been relieved, to provide clearance, by cutting away 20 the back of each blade up to a narrow strip of land, or overhang next to the cutting edge. This overhang has a cylindrical surface spaced equally with the cutting edge from the axis of the reamer, and at the nose 25 which does most of the cutting results in the formation of minute waves in the surface of the bore being reamed, and hence in chattering. To minimize this chattering, the cutting edges have commonly been 30 evenly spaced about the reamer.

The present invention contemplates grinding the reamer to the desired size by cutting a minute angle at each cutting edge to provide a cutting clearance, thereby substantially eliminating any radial land or 35 overhang; and grinding a second angle on the back of each blade to provide a relief clearance. The present method therefore permits the cutting edges to be evenly 40 spaced about the reamer without causing chattering when in use, thereby making it possible to flute solid tooth reamers by a generating process, such as hobbing, and to rotate the reamer continuously in one direction 45 during the grinding operation.

Another object of the invention is to provide a new and improved method for grinding reamers whereby a smooth finish is obtained on the nose, so as to prevent the likelihood of the nose tearing the work in the 50 reaming operation. This object is accom-

plished by passing the nose or guide angle of each blade inwardly over a suitably curved surface formed at one edge of an annular grinding face to first grind and 55 then apply a drag on successive points along said nose. This drag is a very light touching of successive points along the nose by a portion of the receding curved grinding surface after said points have passed 60 the effective grinding area of the grinding face, and serves to produce a very smooth cutting edge.

Heretofore reamers have been provided with a large single guide angle which in 65 passing through the bore being reamed had to remove the excess stock by a concentrated shearing action, thereby frequently tearing or producing rough spots in the work surface.

An important object of the present invention therefore is to provide a novel method for grinding reamers whereby a plurality of adjoining end bevels are ground on the nose of each blade, one or more of said 70 bevels constituting preparatory angles for removing most of the excess stock in the reaming operation, and one bevel merging 75 at a small angle into the crown of the blade and serving to make the finish cut.

A further object of the invention resides in the provision of a new and improved method wherein each blade is positioned to engage the grinding face between the axes of the grinding face and the reamer as said 80 blade is moved across the grinding area to provide the desired clearances; wherein the reamer is angularly adjusted about its axis to obtain the cutting and relief clearances; and wherein each blade is moved over the 85 inner peripheral curved surface of the face when grinding the nose to provide greater clearances on the nose than on the crown because of the inner curvature of the grinding face.

An important object of the invention resides in the provision of a novel method of and machine for grinding reamers wherein the reamer is rotated continuously in one direction to compensate for the inclination of 100 the blades and to position successive blades in the grinding stroke, thereby obtaining

accuracy, speed, uniformity, even cutting clearances, and alignment of the nose angles.

Further objects and advantages will become apparent as the description proceeds.

In the accompanying drawings, Figure 1 is a fragmentary front elevation, partially in section, of a grinding machine for carrying out my invention.

Fig. 2 is a plan view of the grinding machine.

Fig. 3 is a transverse section of the grinding machine taken substantially along line 3-3 of Fig. 2.

Fig. 4 is a longitudinal section of the grinding machine taken substantially along line 4-4 of Fig. 2.

Fig. 5 is a fragmentary view, partially in section, of the gage for setting the work initially relative to the grinding wheel.

Fig. 6 is a fragmentary sectional view of the mechanism for dressing the grinding wheel.

Fig. 7 is a fragmentary section taken along line 7-7 of Fig. 2, and showing the driving connection between the work carriage and the reciprocating mechanism therefor.

Fig. 8 is a fragmentary perspective view of the head stock with the clearance setting mechanism.

Fig. 9 is a detail sectional view of the adjusting cam of the clearance setting mechanism.

Fig. 10 is a detail view of the clearance setting mechanism, showing the cam and dog in position to produce the maximum relief clearance.

Fig. 11 is a vertical section of the oscillating mechanism for the work carriage taken substantially along line 11-11 of Fig. 2.

Fig. 12 is a fragmentary vertical section similar to Fig. 11 taken along line 12-12 of Fig. 2.

Fig. 13 is a vertical section taken along line 13-13 of Fig. 11.

Fig. 14 is a vertical section taken along line 14-14 of Fig. 11.

Fig. 15 is a fragmentary horizontal section of the oscillating mechanism for the work carriage.

Figs. 16 and 17 are diagrammatic views illustrating different stages in one cycle of the grinding operation for a left hand rotary cutter.

Figs. 18 and 19 are views corresponding respectively to views 16 and 17 for a right hand rotary cutter.

Figs. 20, 21 and 22 are similar diagrammatic views showing respectively the positions of the cutter relative to the grinding wheel when the first, the second, and the third of three nose angles are about to be ground.

Figs. 23, 24 and 25 are similar diagram-

matic views showing respectively the specific relation of the shaped grinding face to each of the nose angles through which the drag on the angle surfaces is obtained.

Fig. 26 is a side view of a blade formed with a plurality of nose angles.

Fig. 27 is a fragmentary view showing a cutting edge formed with a single nose angle.

Fig. 28 is a diagrammatic view looking into the grinding wheel, and showing a blade in position across one side thereof.

Fig. 29 is a fragmentary enlarged view of Fig. 18 showing how added clearance is provided on the nose angle or angles by movement over the inner edge of the grinding wheel.

Fig. 30 is a fragmentary sectional view showing the relief generated on the crown of each blade due to the angular position to which the cutter is set about its axis at the beginning of the operation.

Fig. 31 is a fragmentary end view of the cutter showing the relief on the crown of one blade and the relief on the nose.

Fig. 32 is a diagrammatic end view showing a left hand cutter in position for the grinding cut.

Fig. 33 is a view similar to 32 showing the position of said cutter at the completion of the grinding cut.

Fig. 34 is a diagrammatic view showing the position of adjustment of the clearance setting mechanism to provide the cutting clearance.

Fig. 35 is a diagrammatic view showing the position of adjustment of the clearance setting mechanism to provide the maximum relief clearance.

Fig. 36 is an end view of a blade provided with a cutting clearance and a single relief clearance.

Fig. 37 is a view similar to Fig. 36 showing two relief clearances.

While the invention is susceptible of various modifications, I have shown in the drawing and will herein describe in considerable detail the preferred embodiment thereof, but it is to be understood that I do not thereby intend to limit the invention, but aim on the contrary to cover all modifications falling within the spirit and scope of the appended claims.

Referring to the exemplary embodiment of the invention, the method can best be carried out by a machine comprising a bed or base 38 on which are mounted a grinding spindle mounting 39 and a work carriage 40.

The grinding spindle mounting (see Figs. 2 and 3) in the present instance comprises a standard 41 mounted on the rear of the machine bed 38, and formed with a tubular housing 42 which extends substantially transversely of the bed. A long sleeve 43 is slidably mounted in the housing, and is

held against rotation by a key 44. Journaled in the sleeve 43 and longitudinally movable therewith is a rotary spindle 45, the front end of which is provided with a 5 grinding wheel G of suitable form, and the rear end of which is splined to a pulley 46 rotatably mounted in bearings 47 in the rear end of the housing 42. The sleeve 43 is formed on one side with longitudinally 10 disposed rack teeth 48 in mesh with a pinion 49 on a vertical stub shaft 50. The latter is geared through a worm gear 51 and worm 52 in a gear housing 53 on the standard 41 to a shaft 54 having a hand wheel 55, there- 15 by providing means for adjusting the grinding wheel axially to compensate for wear or for variations in size. Mounted on the front end of the sleeve 43 for movement therewith is a dust guard in the form of a 20 cylindrical housing 56 which telescopes with the front end of the housing 42. A hood 57 for the grinding wheel G telescopes with the front end of the housing 56, and can be adjusted by means of a non-rotatable screw 25 58 extending rearwardly through two spaced lugs 59 on the housing, and carrying an adjusting nut 60 between said lugs.

The cutting face of the grinding wheel G may be formed with the desired shape in 30 any suitable manner. Preferably, however, a wheel dressing device, shown in Fig. 6, is provided. This device comprises a bracket 61 on the hood 57. The bracket 61 is formed with a chimney 62 opening into the hood 35 57, and with a sleeve 63 extending radially of the grinding wheel. Reciprocable in the sleeve 63 is a second sleeve 64 formed in its outer surface with a longitudinal gear rack 65. The latter meshes with a pinion 66 40 housed in the bracket 61, and mounted on a shaft 67 having an operating handle 68. Extending through the inner sleeve 64 and pivoted centrally therein for movement laterally of the grinding face is a tool holder 45 69, the outer end of which carries a cutting tool 70, and the inner end of which is provided with a pin 71. The latter extends outwardly through suitable openings in the sleeves 63 and 64, and is pressed against a 50 cam 72 by a coil spring 73 engaging the remote side of the holder 69. The cam 72 has a shape such that in moving the dressing tool 70 over the grinding wheel G by actuating the handle 68, the desired contour will 55 be cut on the grinding face.

To drive the grinding spindle 45, the pulley 46 is connected through a belt 74 to a pulley 75 which is formed integral with a clutch member 76 suitably supported in a 60 bearing bracket 77 on the rear side of the machine base. Extending slidably but non-rotatably through the clutch member 76 is a drive shaft 78 on the rear end of which a pulley 79 is rotatably mounted. This pul- 65 ley is adapted to be driven by a belt 80 de-

riving power from any suitable source, and is formed with an annular clutch flange 81 movable upon reciprocation of the shaft 78 into or out of frictional engagement with the clutch member 76. A heavy coil spring 70 82 disposed between a collar 83 on the shaft 78 and a sleeve 84 on the clutch member 76 tends to move the shaft and pulley forwardly to connect the power. The clutch mechanism is suitably enclosed by a housing 85 secured to the rear side of the machine base, and opening at the top to the inside of the standard 41. The front end of the shaft 78 is slidably and rotatably supported in bearings 86 which are mounted 80 in a tubular sleeve 87 on an inwardly extending bracket 88 formed on a front plate 89 of the base. Rearward movement of the shaft 78 to throw off the power can be effected by means of a screw 90 which is 85 threaded through a cap 91 in the front end of the sleeve 87 into engagement with the front end of the shaft, and which is adapted to be actuated by a suitable hand lever 92.

The work carriage 40 comprises a long 90 narrow slide or sub-base 93, (see Figs. 1 to 4), which is mounted for longitudinal reciprocation on ways 94 on the bed 38, and a table 95 which is mounted on said sub-base for pivotal movement about a stud 96 95 at its left end. Ball bearings 97 mounted in complementary grooves 98 in the sub-base and the table serve to facilitate this movement. The free end of the table 95 is provided with a reduced extension 99 which is movable between two spaced blocks 100 on the sub-base 93, and which is pressed rearwardly by a coil spring 101 mounted in the front block. Rearward movement of the extension 99 can be prevented or limited 100 to the desired extent by means of a hand screw 102 threaded through the rear block 100 and having a lock nut 103. A plate 104 secured to the blocks 100 slidably engages 105 the upper surface of the extension 99, and thereby serves to hold the table 95 against vertical displacement on the sub-base 93.

Adjustably mounted on the right and left ends respectively of the table 95 are a tailstock 105 and a headstock 106 having opposed centers 107 and 108 respectively between which a suitable work arbor 109 is rotatably mounted. The axis of the arbor 109 is located in a plane below that of the grinding spindle axis for a purpose herein- 115 after set forth. In the present instance, each stock is formed with a guideway 110 and provided with a gib 111 (see Fig. 3) respectively engaging and adapted to be clamped against two longitudinal dove-tailed guides 112 formed in the side edges of the table 95. Each gib 111 is supported by a clamp screw 113 extending through the body of the stock. 120

The center 107 of the tailstock 105 is lon- 130

itudinally adjustable in the latter, and can be clamped in position by means of a set screw 114.

The arbor 109 is adapted to support any one of a large variety of cutters or blade holders, and is herein shown supporting a rotary cutter C having inclined or helical blades c. The method is applicable to cutters having solid or inserted blades. The blades of the cutter may have a single nose or guide angle a as shown in Fig. 27, or a plurality of adjoining nose angles, such as angles a', a'', and a''' shown in Fig. 26.

The housing of the headstock 106 is formed on its left end wall, as viewed in Fig. 4, with an inwardly extending core 115 having a central bore 116. Mounted in the bore 116 is a socket member 117 having a tapered bore 118 in which the shank of the work center 108 is seated. Rotatably mounted on the core 115 is a gear 119 having an annular flange 120 on one side concentric with the center 108 and projecting out from the right end of the housing. To prevent back lash in the gearing, a spring pressed brake shoe 121 is mounted in the housing in engagement with the hub of the gear 119. The right end of the housing is closed by two annular wall members 122 and 123 secured respectively to the free end of the core 115 and to the housing, and engaging the inner and outer peripheral surfaces of the flange 120.

Rotatably mounted on a screw bolt 124 (see Figs. 8 and 9) threaded into the end of the flange 120 is a cam member 125 having a peripheral shoulder 126 on its inner end bearing against said flange. The cam member 125 (see Figs. 8, 10, 34 and 35) is formed with a plurality of distinct arcuate surfaces, four surfaces b, b', b'', and b''' in the present instance, which are located respectively at progressively greater distances from the center. A plurality of radial notches 127 (see Fig. 9) are formed in the inner face of the shoulder 126, and are adapted to be selectively engaged by a spring pressed plunger 128 in the flange 120 to hold the cam member 125 yieldingly in any one of its four positions. Mounted rotatably on the center 108, and extending into the wall member 123 is a drive sleeve 129 having a peripheral flange 130 intermediate its ends. A ring 131 is rotatably mounted on the sleeve 129, and may be adjustably secured against the inner side of the flange 130 by means of a pair of clamp screws 132 threaded into the ring and extending through arcuate slots 133 in the flange. The ring 131 is provided with a dog 134 which projects into the path of the cam member 125 to engage any one of the cam surfaces b, b', b'', and b'''.

The outer end of the drive sleeve 129 is formed with a key 135 adapted to interlock with a similar key 136 on a dog 137 secured to the ar-

bor 109. It will be evident that the cam member 125 and the dog 134 constitute an adjustable means in the driving connection between the arbor 109 and the gear 119 whereby the arbor with the cutter C can be relatively adjusted into different angular positions about their common axis.

To initially locate the cutter blades c with respect to the grinding wheel G, the surface b is brought into engagement with the dog 134, and the sleeve 129 is adjusted relative to the ring 130. The correct position is determined by means of a gage (see Fig. 5) which comprises a finger 138 adapted to be moved from an inoperative position into position next to the effective area of the grinding face. In the present instance, the finger 138 is pivotally secured to the lower end of a non-rotatable supporting bar 139 adjustably disposed in a vertical bore 140 which extends through a tubular sleeve 141 forming part of the bracket 61 on the hood 57. The upper end of the bore 140 is closed by a threaded bushing 142. Formed on the upper end of the bar 139 is a threaded shank or stem 143 which extends outwardly through the bushing 142, and which is provided with an adjusting nut 144 and a clamp nut 145. A micrometer ring 146 on the sleeve 141 encircles the adjusting nut 144 and serves to indicate the position of adjustment of the bar 139. To take up lost motion, a coil spring 147 is positioned on the stem 143 between the bar 139 and the bushing 142. The finger 138 is formed with a point 148 adapted to engage the face of a cutter blade c, and with a finger grip 149 by means of which it can be moved upwardly into inoperative position (shown in dotted outline) or downwardly into operative position (shown in full outline). A spring pressed detent 150 mounted in the bar is adapted to selectively engage two notches 151 and 152 formed on the pivoted end of the finger 138 to hold the latter yieldingly in its operative or inoperative position. It will be evident that the gage is adjustable with the hood 57 to adapt it to grinding wheels G of different forms and sizes. In initially setting the cutter C, the upper face of a blade c is moved against the point 148, the dog 134 is positioned against surface b, and the bolts 132 are then tightened to clamp the dog 134 to the sleeve 129.

To slowly and continuously rotate the arbor 109 (see Fig. 4), the gear 119 is in mesh with a pinion 153 on a shaft 154 which is adjustable with the headstock 106, and which extends slidably through a gear housing 155 mounted on the left end of the table 125. The shaft 154 is connected through a train of change speed gears 156 in the housing 155 to a stub shaft 157. By changing the intermediate gears 156 the speed of the shaft 154 can be varied so as to conform to 130

cutters and reamers of different sizes and of different numbers of blades. The stub shaft 157 is connected through a universal joint 158 in vertical alinement with the stud 96, 5 an extensible shaft 159, and a universal joint 160 to a shaft 161 mounted in bearings 162 in the bracket 88. A worm wheel 163 on the shaft 161 meshes with a worm 164 splined to the drive shaft 78.

- 10 To reciprocate the carriage 40 in timed relation to the rotation of the cutter C, a left hand cam 165 and a right hand cam 166 having cam grooves 167 and 168 respectively are mounted on the shaft 161 at opposite sides of the worm wheel 163. Slidably mounted in a longitudinal guideway 169 in the lower surface of the sub-base 93 and held therein by a gib 170 are a pair of slides 171 and 172 having depending pins 173 and 174 engaging the grooves 167 and 168 respectively. A pair of locking pins 175 and 176 are slidably mounted in the front edge of the sub-base 93, and are adapted to engage two depressions 177 and 178 25 in the slides 171 and 172 respectively to lock the latter selectively to the carriage 40. Each pin is provided with a shoulder 179 (see Fig. 7) slidable in a bushing 180, and is yieldingly pressed inwardly by a coil spring 181. Pivottally mounted on the sub-base between the pins 175 and 176 is an interlocking lever 182, the opposite ends of which extend through notches 183 in the bushings 180 and are adapted to engage the 30 shoulders 179 to hold the pins in their retracted positions. The lever serves to prevent both slides 171 and 172 from being locked to the carriage 40 at the same time.

The cam groove 167 (see development dia-

- 40 grams in Figs. 16 to 19) comprises sections *d* and *d'* respectively, formed to give the carriage 40 a slow working movement to the left and a quick return movement to the right. Sections *e* and *e'* of the cam groove 168 are 45 adapted to effect a slow movement of the carriage to the right and a quick return to the left. For convenience the slow movement is designated as the "grinding stroke", and the quick return movement as the "return stroke." The slope or pitch of the cam sections *d* and *e* is such that successive points along the cutting edge of the blade being ground are rotated into grinding position as they move across the effective cutting area 50 of the grinding wheel G. To present the blades *c* of the cutter successively to the grinding wheel G, the velocity ratio of the cam shaft 161 and the arbor 109 is made to equal the number of the blades, and in the present instance is therefore 6:1. To insure accurate grinding, it is necessary that the cutter C be initially correctly positioned relative to the grinding wheel G and the cam grooves.

55 Means is provided for effecting a relative

lateral movement between the face of the grinding wheel G and the cutter C to bevel the ends of the blades *c* (see Figs. 11 to 15). This means preferably is operable to oscillate the table 95 about the pivot stud 96, and 70 comprises a bracket 184 secured to the free end of the table opposite the spring 101. Mounted on the bracket 184 and extending laterally of the sub-base 93 is a cam arm 185 adapted to engage a cam 186 having a cam 75 face, the right end of which is parallel to the sub-base 93, and the left end of which is inclined rearwardly. When single nose angles *a* are to be ground on the blades *c*, a cam 186 with a single angle or bevel *f* on its left 80 end, as shown in Figs. 2, 13 and 15, is provided. When a plurality of nose angles *a'*, *a''*, and *a'''* are to be ground on the blades *c*, a cam 186 with a plurality of angles or bevels *f'*, *f''*, and *f'''* on its left end, as shown 85 in Figs. 16 to 22, is provided.

The cam 186 rests on the front end of a block 187 which is rigidly secured on a forwardly extending shelf 188 of a suitable housing or frame 189. The latter is adjustably mounted on a dove-tailed guide 190 extending laterally of the base 38 and rigidly secured thereto by bolts 191. Formed integral with the frame 189 is a rearwardly extending shell 192 which fits slidably over 90 the edges of a bracket 193 on the rear end of the guide 190. A nonrotatable screw 194 is rigidly secured to the frame 189, and extends rearwardly into threaded engagement with a sleeve nut 195 rotatably mounted in a bearing 196 on the bracket 193. The nut 195 is provided with a hand wheel 197 for adjusting the frame 189 and hence the cam 186 100 toward and from the table 95.

The cam 186 is secured by means of bolts 105 198 to the underside of a slide 199 resting on the block 187. The permit longitudinal adjustment of the cam 186, the slide 199 is formed with a guide way 200 engaging a dove-tailed guide 201 on the block 187. A 110 guard plate 202 on the frame 189 projects over the slide 199 to prevent the entry of foreign matter between the bearing surfaces. An adjusting screw 203 rotatably mounted in a side bracket 204 on the frame 189 has 115 a threaded engagement with the slide 199 and is provided with a suitable handwheel 205. The screw 203 is provided with a micrometer dial 206 for indicating the position of adjustment of the cam 186.

To permit different blades to be moved successively into successive grinding strokes without interference with the grinding wheel, it is necessary that the cutter be returned to its original position out of contact 125 with the wheel. It is obvious that where the blades are sufficiently spaced, this result can be obtained by extending the reciprocation beyond the ends of the cutter, and by causing the grinding wheel to pass between adjacent 130

blades on the return stroke. Preferably, however, the cutter and the grinding wheel are separated laterally during each return stroke. To this end, a left hand cam 207 and a right hand cam 208 are pivotally mounted in the left and right sides respectively of the block 187, and are adapted to selectively engage a cam roller 209 carried by the bracket 184 to oscillate the cutter C away from the grinding wheel G for the quick return movement of the carriage 40. The cam face of each cam terminates next to the pivot in a circular recess 210 which is partially defined by a forwardly extending arm 211. Each cam is pressed rearwardly from the roller 209 by a coil spring 212 mounted between the arm 211 and the adjacent side wall of the frame 189, and is moved forwardly when the roller engages the arm. A pair of pawls 213 and 214 are pivotally mounted in opposite sides of the block 187, and are pressed toward each other by coil springs 215 to respectively engage the free ends of the cams 207 and 208 as the latter are moved forward. Extending through opposite side walls of the frame 189 are a pair of adjustable screws 216 adapted to engage the heels of the pawls to hold the latter inoperative. Only one of the pawls is operative at one time. Upon engagement by a pawl of the associated cam, that cam is held in forward position and in the return movement of the carriage will oscillate the table 95 against the force of the spring 101.

Preferably the grinding wheel G is cup shaped in form, the annular surface constituting the grinding face. To present one side of this face to the work, and to prevent interference between the other side of the face and the work, the grinding spindle 45 is inclined from a perpendicular to the carriage 40. The inner peripheral edge of the grinding face is formed or shaped as best shown in Figs. 23 to 25, to provide a contour which will cause a drag on the ground surface of the cutter nose when the cutter is caused to move inwardly. This drag is a very light touching of the blade by the wheel and is for the purpose of producing a smooth edge thereon. Consequently the inner edge of the grinding face recedes inwardly along curved or substantially elliptical elements. When grinding a cutter having a plurality of nose angles, different points g' , g'' , and g''' on the grinding face respectively apply a drag successively to the nose angles a' , a'' and a''' .

The method and operation will now be described with reference first to a left hand cutter and then to a right hand cutter, both cutters having a plurality of nose angles.

Initially, the gears 156 are changed, if necessary, to correlate the translatory movement of the table 95 and the rotatory move-

ment of the cutter C to the angle of the 65 blades c .

A cam 186 must be used having angles f' , f'' and f''' which will produce angles a' , a'' and a''' of the desired length and size. While the angles a' , a'' and a''' may be varied between certain limits, preferably the angle a' is between 30° and $1^\circ 30'$, say 45° , the preparatory angle a'' is between 2° and 3° , say $2^\circ 15'$, and the guide angle a''' which serves to center the cutter in the bore is about 15° . The cam 186 is adjusted, if necessary, so that it will permit the inward movement of the cutter C at the proper time. The cam 185 is locked to the sub-base 93, the carriage 40 is positioned to begin movement to the left so as to locate the cutter C in the grinding stroke, and the pawl 214 for the right hand cam 186 is rendered inoperative. The position of the pin 173 in the groove 167 corresponding to that of the carriage 40 is indicated in full lines in Fig. 16. The gage finger 138 is now oscillated into operative position to locate a point h (see Figs. 5 and 32) on the cutting face of the grinding wheel G slightly below the horizontal plane of the latter, and the cutter C is set to position the upper left end of the cutting face of one of the blades c against the lower end of the finger. With the cutter in this position, the dog 134 of the clearance setting mechanism is brought into engagement with the cam surface b , and is then secured to the ring 130 by tightening the bolts 132.

The axis of the arbor 109 is substantially 100 below that of the grinding wheel G and below the point h . The effective grinding area of the wheel G thus is located between the axes of the grinding spindle 45 and the arbor 109. Hence the plane of said area is 105 substantially along a chord of the circle of rotation of the blade edges being ground. Each blade c will therefore be relieved, as illustrated in Figs. 30 and 31, along line $h-i$ falling well within the arc $h-j$ about the 110 axis of the cutter C. This relief will be the cutting clearance c' , illustrated in Figs. 34, 36 and 37, for the cutting edge of each blade c .

In the movement of the carriage 40 to the left, the cam arm 185 rides on the cam 186, and the cutter C moves along line $h-l$ to the dotted position shown in Fig. 16 to grind the crown of the blade, the cutter being rotated in timed relation to this movement to bring successive points along the cutting edge of the blade into engagement with the cutting face at the point h . The position of the pin 173 in the cam groove at this stage is illustrated in dotted lines in Fig. 16.

Upon further movement of the carriage, the cam arm 185 rides successively on the angles f' , f'' , and f''' of the cam 186, and

- thereby permits the table to be gradually oscillated varying degrees determined by the inclinations of said angles. The cutter C moves along the broken line $l-m$ to grind the angles a' , a'' , and a''' of the blade. Points g' , g'' , and g''' on the inner peripheral formed surface of the grinding face are tangential respectively to the nose angles a' , a'' and a''' , and apply a drag to said angles after the latter have been ground by their initial contact with the grinding face. Since contact with the grinding face shifts, the junctions of the angles and of the angle a' with the crown of the blade are slightly rounded. The angles a' , a'' and a''' are relieved along lines $n-o$, $n'-o'$, and $n''-o''$ (see Fig. 31) which fall well within the arc $h-j$ about the axis of the cutter. Since the point h is located slightly below the horizontal plane of the grinding wheel G, the angles a' , a'' and a''' are given a greater relief than the crown of the blade. This is due to the additional component of relief generated by the curvature of the formed inner edge of the grinding face, as illustrated in Figs. 29 and 31. The position of the cutter C at the completion of the beveling cuts is the same as that of the cutter with the single nose angle a shown in Fig. 33.
- As the carriage 40 moves into its extreme left position, the roller 209 engages the arm 211 of the cam 207, thereby moving the latter forwardly and permitting it to be engaged by the pawl 213. The pin 173 in the groove 167 and the cutter C assume positions shown in full lines in Fig. 17. In movement of the carriage 40 to the right, the roller 209 in leaving the recess 210 of the cam 207 oscillates the table 95 forwardly beyond its central position, and then rides along the cam 207, thereby causing the cutter C to return along line $m-p$ and line $p-q$ out of engagement with the grinding wheel G. As the carriage moves into its extreme right position, in which the pin 173 and the cutter C assume positions illustrated in dotted outline in Fig. 17, the roller 209 disengages the pawl 213, thereby releasing the cam 207 and permitting the spring 101 to return all parts to their initial positions. During the return movement of the carriage, the cutter C is rotated to an extent such that in the next operation the following blade is automatically positioned in the grinding stroke.
- The cyclic movement of the carriage 40 is repeated until all the blades c are ground to the desired size and with the desired clearances. When all the blades c have been ground with a cutting clearance c' , the dog 125 is adjusted to adjust the cutter C about its axis for grinding one or more relief clearances. The clearances to be ground vary with different cutters. Fig. 35 shows the dog 134 engaging the cam surface b'' to position the cutter C for grinding a single maximum relief clearance c'' . The nose of a blade ground with clearances c' and c'' is shown in Fig. 36. By turning the cam surfaces b' and b'' selectively into position for engagement by the dog 134, intermediate relief clearances c''' and c'''' may be ground. A blade ground with a cutting clearance c' and relief clearances c'' and c''' is shown in Fig. 37. Large cutters are preferably ground with the relief clearance c'''' (not shown) as the maximum instead of the relief clearance c'' . In some instances, it may be desirable to partially grind the relief clearance before grinding the cutting clearance to the desired size.
- In grinding a right hand cutter, the operation is similar in principle. Initially, the cam 166 is operatively connected to the sub-base 93, the cutter is set with the carriage in position to begin movement to the right, the pawl 213 is rendered inoperative, and the cam arm 185 is resting on the inclined portion of the cam 186. Movement of the carriage to the right results in moving the cutter C first along broken line $r-s$ to bevel the end of the blade, and then along line $s-t$ to grind the crown of the cutting edge (see Figs. 18 and 19). At the completion of the cut, the cam 208 is moved into and held in operative position, so that in the return movement of the carriage, the cutter moves first along line $t-u$ and then along line $u-v$. Upon disengagement of the pawl 214 with the cam 208, the cutter moves along line $v-r$ into its initial position.
- By the above method each blade is so ground that the helical cutting edge of the crown lies in a cylindrical area and the beveled edge lies in an area tapering from said cylindrical area.
- Rotating the cutter continuously in one direction in timed relation to the translatory movement causes successive points along each blade to be moved into engagement with the grinding face at the point h during the cutting stroke, and causes the blades to be positioned consecutively in the grinding stroke in successive cycles. By providing a cutting clearance, the cutting edge is ground to size and relieved in a single machine operation, and a radial land is substantially eliminated. Since the nose of the cutter has no radial land and since its angles have greater clearances than the crown of the blades, the cutter will not chatter when in use. By providing a plurality of nose angles, the desired diameter of the reamer is reached gradually. Each of the angles removes a small amount of metal, thereby tending to produce minute shavings. By applying a drag to these angles, the cutter nose is formed with a smooth accurate cutting edge.
- I claim as my invention:
1. The method of relief grinding the heli-

- cal blades of cutting tools, which comprises causing a combined or simultaneous reciprocatory and rotary motion between a blade-holder and a grinding wheel, and causing a 5 relative approaching movement between said blade-holder and said wheel during an intermediate state of such combined reciprocatory and rotary motion to grind a deflected end section on the blade.
- 10 2. The method of relief grinding the helical blades of cutting tools which comprises causing a combined or simultaneous reciprocatory and rotary motion between a blade-holder and a grinding wheel, and causing a 15 series of relative approaching movements between said blade-holder and said wheel during a predetermined stage of such combined reciprocatory and rotary motion to grind a plurality of differently inclined contiguous nose angles on each blade, the first approaching movement being slight to cause the first nose angle ground and adjoining the crown of the blade to be small.
3. The method of relief grinding cutters 25 having blades with helical cutting edges which comprises imparting a continuous rotary motion to the cutter, a continuous reciprocatory motion to said cutter across a grinding element, which projects into the 30 circle of revolution of said cutter, in timed relation to said first mentioned motion, and a relative approaching movement between said cutter and said grinding wheel at a predetermined point in said reciprocation; 35 to grind a deflected section on each blade, said grinding element being removed from the surface being ground at appropriate times to pass from one blade to another.
4. The method of relief grinding cutters 40 having helical cutting edges which comprises imparting a continuous rotary motion to the cutter, and a continuous reciprocatory motion to said cutter across a grinding element, which projects into the circle of revolution of the cutter, in timed relation to said 45 first mentioned motion, said grinding element being removed from the surface being ground at appropriated times when passing from one edge to another edge.
5. The method of relief grinding cutters 50 having helical cutting edges which comprises imparting a continuous rotary motion to the cutter, a continuous reciprocatory motion to said cutter across a grinding element, 55 which projects into the circle of revolution of the cutter, at a ratio corresponding to the number of edges to be ground so as to compensate for the curvature of said edges and to move consecutive edges successively into 60 position to be ground, and separating said grinding element and said cutter laterally of said cutter during a predetermined stage of said reciprocatory motion to permit movement of said edges successively into grinding 65 position.
6. The method of relief grinding the blades of cutting tools which comprises positioning the blade to engage a grinding wheel between the axes of said grinding wheel and the tool holder, imparting relative reciprocatory motion between said tool holder and said grinding wheel, and imparting a relative approaching movement between said tool holder and said wheel during a predetermined state of said reciprocatory 70 motion to grind a deflected section on one end of said blade, the positioning of said blade serving to produce a relief on the blade and on the deflected section thereof.
7. The method of grinding the blades of 75 cutting tools, which comprises imparting a reciprocatory movement to a blade across a grinding wheel having an annular grinding face, the inner peripheral edge of which is formed to recede into the annulus of said wheel, and imparting a relative approaching movement between said blade and said face during a predetermined stage of said reciprocatory movement to move one end of said blade over said formed edge to grind and 80 drag a deflected section of said blade.
8. The method of relief grinding cutting tools having blades with helical cutting edges, which comprises imparting a continuous 85 rotary motion to the tool, imparting a relative reciprocatory movement between said tool and a grinding wheel having an annular face, said face projecting into the circle of revolution of the tool, imparting a relative approaching movement during a 90 predetermined stage of one stroke of each double reciprocation between said tool and said wheel to move the nose of said tool over the inner peripheral edge of said face, and separating said tool and said wheel 95 during the other stroke of each double reciprocation.
9. The method of grinding blades with 100 helical cutting edges which comprises imparting a continuous rotary motion to the blade support, imparting a relative reciprocatory movement between said support and a grinding element, said rotary motion and said reciprocatory movement being timed to compensate for the helix of each 105 edge and to present the blades successively to said grinding element during consecutive cutting strokes of said reciprocatory movement, and separating said support and said grinding element during the return strokes 110 of said reciprocatory movement.
10. The method of relief grinding cutters 115 having blades with helical cutting edges, which comprises positioning the cutter so that each blade will contact with a grinding element between the axes of said cutter and said element, feeding said grinding element into the circle of revolution of said cutter, imparting a continuous rotary motion to said cutter, imparting a relative recipro- 120
- 125

- catory movement between said cutter and said element in such timed relation to said rotary motion so that the blades are presented successively to said element in consecutive reciprocations, and imparting a relative approaching movement at a predetermined point in each reciprocation between said cutter and said element to grind a deflected portion of each blade, said element being removed from the blades at appropriate times to permit passage from one blade to another blade. 5
11. The method of grinding cutters having blades with helical cutting edges, which comprises positioning the cutter so that each blade will contact with a grinding element between the axes of said cutter and said element, imparting a continuous rotary motion to said cutter, imparting a relative reciprocatory movement between said cutter and said element in such timed relation to said rotary motion that the blades are presented successively to said element in consecutive reciprocations, and adjusting said cutter about its axis between reciprocations and after any complete rotation of said cutter to present different parts of the back of each blade to said element. 10
12. The method of relief grinding the helical blades of cutting tools which comprises causing a combined or simultaneous reciprocatory and rotary motion between a blade holder and a grinding wheel, and causing a relative and variable approaching movement between said blade holder and said wheel during a predetermined stage of such combined reciprocatory and rotary motion to grind a progressively increasing deflection on a section of the blade. 15
13. The method of grinding the blades of rotary cutting tools which comprises positioning the tool so that the blades will be presented successively to a grinding element at an angle to the grinding face to grind one of two clearances, i. e., a cutting clearance to the desired diameter at the cutting edge, and a relief clearance back of said cutting clearance, imparting a relative reciprocatory movement between said tool and said grinding element, and adjusting said tool about its axis between reciprocations so that the blades will be presented successively to said element at a different angle to the grinding face to grind the other of said clearances. 20
14. The method of relief grinding the blades of cutting tools comprising positioning the cutter to present a blade to a grinding wheel having an annular grinding face between the axes of said grinding wheel and the blade support, with the face of the blade nearest the axis of said grinding wheel, relatively moving the blade longitudinally across said face to grind the crown, and relatively moving the blade laterally during a predetermined stage of said first mentioned move- 25
- ment to pass the same over the inner peripheral edge of said grinding wheel to grind a deflected end section of the blade, the curvature of said grinding face resulting in the grinding of a greater relief on said deflected end section than on the crown of the blade. 70
15. The methods of grinding the blades of rotary cutting tools which comprises positioning the tool to present a blade to the grinding element between the axes of said tool and said element so as to grind a relief clearance on the back of the blades, imparting a relative reciprocatory movement between said tool and said grinding element, 75 and adjusting said tool about its axis between reciprocations to present the blade to said element in a different position between said axes to grind the blade to correct diameter with a cutting clearance at 80 the cutting edge. 85
16. The method of relief grinding rotary cutters having helical blades which comprises initially positioning the cutter to present a blade to the side face of an annular grinding element between the axes of said cutter and said element, with the face of the blade nearest the axis of said element, to grind one of two clearances, i. e., a cutting clearance to the desired diameter at the cutting edge and a relief clearance back of the cutting clearance, imparting a relative reciprocatory and rotary movement between said tool and said grinding element, imparting a relative approaching movement between said cutter and said element to move one end of the blade over the inner peripheral edge of said grinding face during a predetermined stage of said reciprocation so as to grind a deflected end section on the 90 blade, and adjusting said cutter about its axis between reciprocations, into another position to present the blade to said element in a different position between said axes to grind the other of said clearances, the 95 positioning of the cutter relative to said grinding face for the grinding of said clearances resulting in the grinding of greater clearances on said deflected end section than on the crown of the blade. 100
17. A relief grinding machine having, in combination, a grinding wheel, a support for a rotatable blade holder having a blade oblique to its axis of rotation, means for rotating said blade holder, means for reciprocating said grinding wheel and said blade holder relatively to each other in a grinding stroke with said wheel projecting into the circle of revolution of said holder and in a return stroke, means for defining a line of grinding contact conforming, in part, to an elongated blade crown, and a portion receding from such crown in the plane of the blade at one end thereof, and means for automatically separating said 110 115 120 125 130

wheel and said blade holder at the end of said grinding stroke and returning said blade holder at the end of said return stroke out of contact with said wheel to the succeeding grinding stroke.

18. A relief grinding machine having, in combination, a grinding wheel, a support for a blade holder having a blade that is to be ground, means for bodily moving said blade holder and said grinding wheel relative to each other to grind said blade, and means for defining a line of grinding contact conforming, in part, to an elongated blade crown and a portion receding from such crown in the plane of the blade at one end thereof.

19. A relief grinding machine having, in combination, a grinding wheel, a support for a rotatable blade holder having an inclined blade that is to be ground, said holder serving to present the blade to said wheel with the latter projecting into the circle of revolution of said holder, means for continuously rotating said holder, and means for reciprocating said holder axially as it is being rotated to move said blade across said wheel in a grinding stroke and to return said blade out of contact with said wheel in a return stroke.

20. A grinding machine having, in combination, a grinding wheel, a support for a cutter having a plurality of longitudinally inclined blades, means for reciprocating said support relative to said grinding wheel to move the cutter in one direction in grinding contact with said wheel and in the other direction out of contact with said wheel, and means for continuously rotating said cutter in one direction in timed relation to said reciprocation to compensate for the inclination of each blade as it is being ground and to present different blades singly to said grinding wheel in successive reciprocations.

21. A grinding machine having, in combination, a grinding wheel, means adapted to support a cutter having a plurality of longitudinally inclined blades, means for effecting a relative reciprocation between said grinding wheel and said cutter to present said blades singly to said grinding wheel, means for automatically effecting a lateral separation between said grinding wheel and said cutter throughout one stroke of each reciprocation, means for continuously rotating said cutter in timed relation to said reciprocation so as to compensate for the inclination of each blade as it is being ground, and to move a different blade into position during said separation to present said last mentioned blade to said grinding wheel in the grinding stroke immediately following.

22. A grinding machine having, in combination, a grinding wheel, a support, a table pivotally mounted on said support and

adapted to support a cutter having longitudinally inclined blades, means for reciprocating said support to provide a grinding stroke and a return stroke for each blade, means for oscillating said table to separate said cutter from said grinding wheel at the completion of said grinding stroke, and to reposition said cutter at the completion of said return stroke, and means for automatically rotating said cutter to compensate for the inclination of each blade being ground, and to present different blades singly to said grinding wheel in successive grinding strokes.

23. A grinding machine having, in combination, a grinding wheel, means for supporting a cutter having a plurality of blades, means for relatively reciprocating said cutter longitudinally across said grinding wheel to grind the crown of each blade, and means for moving said cutter laterally toward and from said grinding wheel in predetermined relation to said reciprocation at predetermined points in the latter to move the end of each blade over the edge of said grinding wheel so as to produce an end bevel receding from said crown.

24. A grinding machine having, in combination a grinding wheel, a support for a cutter having a plurality of blades, means for moving said cutter through a series of cycles, each cycle comprising a grinding stroke across said grinding wheel to grind the crown of a blade and a movement of said cutter transversely of said grinding wheel at one end of said grinding stroke to move one end of said blade over an edge of said grinding wheel to bevel the end of said blade, a separating movement between said cutter and said grinding wheel at the completion of said grinding stroke, a free return stroke, and an approaching movement between said cutter and said grinding wheel at the end of said return stroke to reposition said cutter in grinding relation to said grinding wheel, and means for automatically rotating said cutter to present different blades successively to said grinding wheel in successive cycles.

25. A grinding machine having, in combination, a grinding wheel having an annular grinding face, the inner edge of which is formed with a curved surface gradually receding from the plane of said face, a table for supporting a cutter having a generally longitudinal blade, means for reciprocating said table to move said blade across said grinding face, and cam means operable at predetermined points in said reciprocation to effect an oscillation of said table to move part of said blade over the inner edge of said grinding face and then to return said blade to its normal position.

26. A grinding machine having, in combination, a grinding element having a flat

- grinding surface, one edge of which is formed with a curved surface gradually receding from the plane of said grinding surface, a support for a blade, means for moving said blade across said grinding surface, and means operable through said movement to cause a lateral movement of one end of said blade over said curved surface.
27. A grinding machine having, in combination, a grinding wheel, a support for a blade holder adapted to present a blade to said wheel, means for moving said blade holder and said wheel relative to each other, and means for defining a line of grinding contact conforming, in part, to an elongated blade crown and a plurality of differently inclined contiguous sections receding from said crown in the plane of the blade at one end thereof.
28. A grinding machine having, in combination, a grinding element having an annular grinding face, the inner edge of which recedes inwardly, means for supporting a generally longitudinal blade, means for reciprocating said supporting means to move said blade longitudinally across one side of said face, and cam means operable through said reciprocation to effect a plurality of different successive movements of said supporting means laterally of said face to move one end of said blade in different directions over said inner edge to grind and drag a plurality of contiguous nose angles on said blade.
29. A grinding machine having, in combination, a grinding wheel, a carriage for supporting a cutter having helical blades, means operable to move said carriage slowly in one direction to carry said cutter across the face of said grinding wheel and operable to return said carriage quickly to its initial position, means operable to swing said cutter toward said grinding wheel near the completion of the slow movement to bevel the ends of cutter blades, and to hold said cutter out of engagement with said grinding wheel on the return movement, and means for automatically rotating said cutter continuously in one direction in timed relation to the reciprocatory movement of said carriage to compensate for the inclination of the blades and to position different blades respectively in successive grinding strokes.
30. A relief grinding machine having, in combination, a grinding wheel, a carriage for supporting a cutter with inclined blades, means operable to effect a relative reciprocatory movement between said cutter and said grinding wheel longitudinally of said cutter with said wheel projecting into the circle of revolution of said cutter, means operable to effect a relative movement between said cutter and said grinding wheel transversely of said cutter at a predetermined point in each reciprocation to bevel the end
- of the blade, and means for continuously rotating said cutter in one direction in timed relation to said reciprocatory movement to compensate for the inclination of the blades and to position different blades respectively in successive grinding strokes.
31. A grinding machine having, in combination, a grinding wheel, a support for a cutter having a generally longitudinal blade, means for effecting a relative movement between said wheel and said support to move said blade across said wheel, and means for effecting a relative and a progressively increasing lateral movement between said wheel and said support during a predetermined stage of said first mentioned movement to grind a progressively increasing deflection on a section of the blade.
32. A grinding machine having, in combination, an annular grinding wheel, a support for a cutter having generally longitudinal blades, the axis of said cutter being substantially below that of said grinding wheel, means for moving said cutter longitudinally to feed its blades singly across the annular face of said wheel, grinding contact occurring above the axis of said cutter and below the axis of said grinding wheel, and means for causing lateral movement of one end of each blade across the inner peripheral edge of the grinding face into said grinding wheel.
33. A grinding machine having, in combination, a grinding wheel having a circular grinding face, a support for a cutter, the axis of said cutter being spaced from that of said grinding wheel, means for relatively moving said grinding wheel and said support longitudinally of said cutter to feed a blade of said cutter across said face of said grinding wheel, said blade being set to engage the latter between the axes of said grinding wheel and said cutter, and means operable through said movement for automatically moving said cutter and said grinding wheel laterally relative to each other to move the blade over a circular edge of said grinding face to provide a bevel having a relief or clearance.
34. A grinding machine having, in combination, a grinding wheel having an annular cutting face which is inclined to present one side as the effective grinding area, a support for a cutter, means for reciprocating said support to move said cutter across said effective grinding area, and means for moving said cutter transversely to move one end thereof across the inner edge of said effective area.
35. A relief grinding machine having, in combination, a grinding wheel, a support for a cutter having a longitudinal helical blade, means operable to move said cutter in a closed cycle and to present said blade to said grinding wheel during a portion of

said cycle with said grinding wheel projecting into the circle of revolution of said cutter, and means for continuously rotating said cutter during said cyclic movement.

5 36. A grinding machine having, in combination, a grinding wheel, a support for a cutter having a plurality of longitudinal inclined blades, means operable to move said cutter through a series of predetermined 10 cycles to present one of said blades to said grinding wheel during a portion of each cycle, and means for continuously rotating said cutter in timed relation to said cyclic movement to present the blades consecutively to 15 said grinding wheel in successive cycles.

37. A grinding machine having, in combination, a grinding wheel, a reciprocatory work carriage, drive means for said carriage, said means including a cam adapted 20 to move said carriage slowly in one direction and quickly in another direction, and a cam to drive said carriage slowly in said last mentioned direction and quickly in said first mentioned direction, and means for selectively connecting said cams operatively to 25 said carriage.

38. A grinding machine having, in combination, a hollow grinding wheel, a reciprocatory slide, a pivotal table on said slide, 30 a support for a cutter on said table, means for reciprocating said slide, and means operable through said reciprocation to oscillate said table to move said cutter into said wheel and out again at one end of each 35 reciprocation.

39. A relief grinding machine having, in combination, a grinding wheel, a support for a cutter having a plurality of helical blades, means for moving said support through a 40 grinding stroke slowly in one direction to move a blade across the face of said grinding wheel with said wheel projecting into the circle of revolution of said cutter, and quickly through a return stroke in the other 45 direction out of contact with said wheel, and means for rotating said cutter during said grinding stroke to compensate for the inclination of the blade and during said re-

turn stroke to move another blade into position to be ground at the beginning of 50 the succeeding grinding stroke.

40. A grinding machine having, in combination, a grinding wheel having a grinding face with a circular edge, said edge being formed with a surface receding from 55 said face, a support for a cutter having a blade, the axis of said cutter being spaced from that of said grinding wheel, means for relatively moving said grinding wheel and said support longitudinally of said cutter 60 to feed the blade across said face, said blade being set to engage the latter between the axes of said grinding wheel and said cutter and to one side of the axis of said grinding wheel, and means operable during said 65 movement to automatically move said cutter and said grinding wheel laterally relative to each other so as to move the blade over said formed surface, thereby shifting the point of grinding contact between said cutter and said grinding face.

41. A grinding machine having, in combination, a grinding wheel, a support, a table pivotally mounted on said support, said table being adapted to support a cutter having 75 a blade to be ground, means for reciprocating said support to move said blade across the effective grinding area of said grinding wheel, and means for oscillating said 80 table to move said cutter laterally of said grinding area, said last mentioned means comprising a stationary cam for controlling said last mentioned movement in one direction of reciprocation, a movable cam adapted to pivot and hold said table away from 85 said grinding wheel upon reciprocation in the other direction, and trip means for holding said movable cam in operative position and serving to move said movable cam into operative position and to release said 90 movable cam at opposite ends respectively of said reciprocation.

In testimony whereof, I have hereunto affixed my signature.

GERARD A. DE VLIEG.
